Paul M. Corp, Alliance, Ohio, assignor to Allianceware,
Inc., Alliance, Ohio, a corporation of Delaware

Application November 13, 1958, Serial No. 53,364

Term of patent 14 years

(Cl. D4—4)

Figures 3 and 4 are vertical sections on the lines 3—3 and 4—4, respectively, of Figure 1.

The dominant features of my design reside in the portions shown in full lines.

I claim:

The ornamental design for a bathtub, as shown and described.
